PISTON

William Arthur Oubridge, Coventry, England

Application July 27, 1934, Serial No. 737,292
In Great Britain December 16, 1933

2 Claims. (Cl. 309—14)

This invention relates to pistons of the light metal alloy type in which the piston rings, or certain of them, are mounted in an incast carrier surrounding the upper part of the piston and made of a metal or alloy having greater wear-resisting qualities than that of the piston itself.

Where the piston ring carrier is made of grey cast iron the difference between its coefficient of thermal expansion and that of the piston makes it essential to provide some means for preventing the development of relative movement between the carrier and the piston. It is also desirable to provide against the possible risk of the carrier being displaced from the top of the piston by the inertia forces set up by the reciprocating piston even in those cases where the light metal alloy piston and the piston ring carrier have a common coefficient of expansion. For example, the piston may be of aluminium alloy with a silicon content of 12% to 14% and the cast iron carrier may be of austenitic structure with a nickel content of 18% to 20%, or a nickel content of 16% and a copper content of 2% to 3%; or a nickel content of 15%, a copper content of 6% and a chromium content of 2.5%; or a manganese content of approximately 5% together with a nickel content of not more than 12% with or without aluminium and/or copper up to 5%. In addition to the use of nickel, and/or copper and manganese, suitable proportions of chromium, molybdenum, vanadium or titanium may be employed to modify the hardness and wear resistance of the material of the piston ring carrier.

The object of the present invention is to provide new or improved methods of and means for locking the carrier to the piston.

According to the present invention a firm connection between the piston and the piston ring carrier is obtained by forming the latter with castellations which when the piston is cast about the carrier extend to and form part of the outer peripheral surface of the piston and effectually prevent any tendency toward angular movement of the carrier relatively to the piston. The connection is further secured by means of a locking ring which is inserted in an annular groove formed around the piston and the castellations of the carrier after the casting process, said ring by its engagement with both the piston and the carrier preventing any tendency for relative movement to take place between the piston and the carrier in an axial direction.

In the accompanying drawing,

Figure 1 is a general view of the improved piston ring carrier per se.

Figure 2 is a part sectional view of a piston provided with a piston ring carrier in accordance with this invention.

As will be seen from Figure 1, the piston ring carrier *a* consists of a solid ring of substantial section having castellations *a*¹ which may be formed either on one side only, as shown, or on both sides.

After the piston *b* is cast about the ring an annular groove *c* is formed in the piston around the castellated portion of the ring *a* to receive a locking ring *d* of steel or other suitable material, as shown in Figure 2.

The said carrier ring may be made either of grey cast iron or of austenitic iron of substantially the compositions above set forth. In the former case it is essential to provide against any slackness that may develop between the carrier ring and the piston owing to their different coefficients of expansion, and in the latter case, where the respective coefficients of expansion of the carrier ring and piston are approximately alike, it is still necessary to provide against the possible risk of the carrier being displaced from the top of the piston by the inertia forces set up by the rapid reciprocatory motion of the latter.

In both cases the use of a carrier ring of the kind described provides an adequate solution of the difficulty, the castellations *a*¹, by their intimate engagement with the piston, effectually preventing any tendency for the carrier ring to rotate relatively to the piston, whilst the locking ring *d*, by its engagement with both the piston and the carrier ring, resists any tendency for the axial displacement of the latter.

The said locking ring may, if desired, be incast around the carrier and piston and, in addition to its primary function as a carrier ring locking device, may be made of such external diameter as to reduce the clearance between the piston head and the cylinder above the first or upper piston ring.

I claim:—

1. A piston comprising a cylindrical light metal alloy casting forming the body thereof, a hard metal band incast around said body to receive piston rings and having castellations extending to and forming part of the outer peripheral surface of said body, and a ring surrounding and interlocking with said body and the outer ends of said castellations for preventing displacement of said band.

2. A piston comprising a cylindrical light metal alloy casting forming the body thereof, a hard metal band incast around said body to receive piston packing devices and having castellations extending to and forming part of the outer peripheral surface of said body, and means alternately engaging said body and said castellations for preventing displacement of said band.
